UNITED STATES PATENT OFFICE.

ROBERT A. GALLY, OF CINCINNATI, OHIO, ASSIGNOR TO THE BALDWIN COMPANY, OF CINCINNATI, OHIO,

MUSIC-SHEET-TRAVEL-CONTROL PERFORATIONS.

1,271,886.

Specification of Letters Patent.

Patented July 9, 1918.

Application filed December 17, 1917. Serial No. 207,640.

To all whom it may concern:

Be it known that I, ROBERT A. GALLY, a citizen of the United States, and residing at Cincinnati, in the county of Hamilton and State of Ohio, have invented certain new and useful Improvements in Music-Sheet-Travel-Control Perforations, of which the following is a specification.

Prior art of control of the rewind and repeat travel of a music sheet from perforations therein originated in M. Gally, #222,030, November 25, 1879, and developed in Arno #596,768, January 4, 1898, but in the first instance foot or hand power was used, and although in Arno an electric drive was employed, he provided for his electric motor being stopped from a perforation in the sheet whenever it had returned to its commencement end. Thus in neither of these devices did it make any difference as to what positions the rewind and repeat perforations were located relative to the edge of the music sheet, and no such transverse location was set forth by either of these inventors, but when no automatic stop perforation is employed for stopping the drive motor, or when foot power is employed with such automatic controls by the rewind perforations 1 or 2, and repeat perforation 3, especially when the front end of the music sheet 4 is slanted away from its edges at its commencement end 5, which is usually so, and has a means as 6 for attaching to the take-up device of the music player, it does become important to locate the repeat perforation 3 nearer to an edge 7 of the music sheet 4 than the distance of any rewind perforation 1 from the same edge of the music sheet, or a rewind perforation 2 from the other edge 8 of the music sheet 4, for unless the repeat perforation 3 is nearer to an edge of the sheet than the rewind perforation 1 or 2, the corresponding apertures of the tracker bar 9 controlled by the said perforations would be in such relation to the slanted edge or edges of the sheet as to allow the rewind aperture 10 or 10^a to remain open later than the repeat aperture 11 as such a slanted end music sheet was drawn over said tracker, with the result that the rewind pull

on the sheet would prevent the user from completing its placing in the apparatus and attaching to the take-up device of the player for the forward travel of the sheet 4 to play the note perforations 12, all which is 55 avoided by the novel positioning of the rewind and repeat perforations as above described, and as set forth in the accompanying drawing, and being what is claimed as my invention, which is:—

1. A music sheet having perforations for notes alined therein in several rows longitudinally of the sheet, a perforation in another alinement to effect the shifting to the rewind travel of the sheet, and another perforation, 60 in another alinement than any of the aforesaid perforations to effect the shifting to the repeat travel of the sheet for replaying, the said perforation for repeat travel being nearer to an edge of the sheet than is the 65 perforation for rewind travel.

2. A music sheet having perforations for notes alined therein in several rows longitudinally of the sheet, a perforation in another alinement to effect the shifting to the 70 rewind travel of the sheet, and another perforation, in another alinement than any of the aforesaid perforations, to effect the shifting to the repeat travel of the sheet for replaying, the said repeat perforation being 75 nearer to one edge of the sheet than the said rewind perforation is to the other edge of the sheet.

3. A music sheet having perforations for notes alined therein in several rows longitudinally of the sheet, a perforation in another alinement to effect the shifting to the 80 rewind travel of the sheet, and another perforation, in another alinement than any of the aforesaid perforations to effect the shifting to the repeat travel of the sheet for replaying, the said perforation for repeat travel being 85 nearer to an edge of the sheet than is the perforation for rewind travel, and the forward end of the said sheet being slanted 90 away from its edges at that end.

4. A music sheet having perforations for notes alined therein in several rows longitudinally of the sheet, a perforation in another alinement to effect the shifting to the 95 repeat travel of the sheet for replaying, the said perforation for repeat travel being 100 nearer to an edge of the sheet than is the perforation for rewind travel, and the forward end of the said sheet being slanted away from its edges at that end.

wind travel of the sheet, and another perforation, in another alinement than any of the aforesaid perforations, to effect the shifting to the repeat travel of the sheet for repeating, the said repeat perforation being nearer to one edge of the sheet than the said rewind perforation is to the other edge of

the sheet, and the forward end of the said sheet being slanted away from its edges at that end.

ROBT. A. GALLY.
